CODED TRACK CIRCUIT SIGNALING
SYSTEM

Louis Girardin, Paris, France, assignor, by mesne assignments, to The Union Switch & Signal Company, Swissvale, Pa., a corporation of Pennsylvania

Application January 25, 1940, Serial No. 315,553
In France April 15, 1939

12 Claims. (Cl. 246—34)

This invention relates to track circuit signaling systems for railways and the like of the kind in which the track rails are sub-divided into insulated block sections to which coded signaling currents are supplied to control the operation of signals on the track or train or both in accordance with traffic conditions.

The broad object of this invention is to reduce the power requirements and increase the utility of railway signaling systems of the just defined coded track circuit class.

A more specific object is to provide improved facilities for approach controlling various functions of coded track circuit signaling systems without the aid of line wires between signal locations.

Other objects are to utilize these improved approach control facilities for the purposes of: (1) economizing trackway and other signaling system energy; and (2) extending the distance over which the approach of a train may be detected by energy that is transmitted through the track rails.

In a coded track circuit signaling system which includes the approach control facilities of this invention the devices by means of which the coded signaling currents are supplied to the track circuits and the devices responsive to these currents are rendered operative only upon the approach of a train or vehicle. That approach, furthermore, is arranged to be indicated as far as three block sections ahead of the oncoming train so that, for example, the approach of a train or vehicle to a level crossing, track divergence or station may be detected within a three-block range without involving the provision of any additional control circuits.

According to the principal feature of the invention, each of the track sections is provided with two approach detector relays arranged at the exit end of the section and adapted to be energized respectively by alternating and direct signaling currents supplied to the track at the entrance end of the section in accordance with traffic conditions, these relays being arranged, in accordance with their relative conditions of operation under the action of the track signaling currents, to control the operation of the code transmitting and receiving apparatus upon the approach of a train or vehicle so as to give the required signal indications and also, if desired, to effect the indication at the desired point of the approach of the train or vehicle.

The invention is illustrated by way of example in the accompanying drawings of which Fig-

ure 1 is a diagrammatic view of a single track section illustrating the principal feature of the invention. Fig. 1a represents the different forms of energy which at various times are transmitted by the track circuit of Fig. 1. Figures 2, 2a and 3, when placed end to end with Figure 2 on the left and Figure 3 on the right, constitute a diagrammatic view of a number of successive track sections provided with signaling apparatus arranged in accordance with one form of the invention, one of the track sections being shown as including a level or highway crossing.

Figure 4 is a chart showing the operative conditions of certain relays of the system of Figures 2 and 3 as a train or vehicle proceeds through the track sections in succession.

Figure 5 is a detail view showing, in a simplified form, the connections for controlling the operation of a level or highway crossing indicator.

In the several views of the drawings like reference characters designate corresponding parts. Referring first to the composite diagram of Figs. 2—2a—3 the improvements of this invention are there disclosed in association with a coded track circuit system of automatic block signaling for a stretch of railway track over which it will be assumed that traffic moves in the single direction indicated by the arrows, or from left to right in the diagram. The protected stretch of this track is divided into the customary block sections V1, V2, V3, etc., by insulated rail joints and the rails of each section form a part of a new and improved track circuit combination which is most clearly shown in Fig. 1 and which will be described presently.

Installed at the entrance end of each of the block sections V of Figs. 2—2a—3 is a wayside signal S which governs the passage of traffic into the block in the usual way. Included in the block which signal S4 guards are two sections V4^a and V4 and embraced by section V4 is an intersecting highway PN. Installed at the level crossing which this highway forms is the usual crossing indicator or signal SPN which warns the users of the highway whenever a train approaches.

Automatic block system of coded track circuit signaling

The just named wayside signals S form a part of the coded track circuit system of automatic block signaling that was previously mentioned. Further included in that system are code following track relays TR installed at the entrance

ends of the several track sections and operated by energy received from the rails thereof; master track batteries TB installed at the exit ends of the sections for the purpose of supplying the rails thereof with the relay operating energy just referred to; similarly located coding devices CR which code this operating energy by periodically interrupting the master rail supply circuit; code transmitters CT which operate each of the exit end devices CR at one or another of the usual plurality of distinctive code rates; and decoding relays H and J at each signal location which are controlled by the track relay TR that is there installed.

In the illustrative form represented the coded system of automatic block signaling is of the three-indication variety; it is operated by 180 and 75 pulse per minute "master" signal control codes that selectively are supplied to the track rails at the exit end of each section; and it requires no line wires between signal locations. In it each set of decoding relays H and J performs the usual functions of: (1) governing the indication of the signal S at the relay location; and (2) selecting the coding of the master signal control energy which is supplied to the section to the rear. In the arrangement shown the first of these functions is effected by contacts 21 and 34 of relays H and J while the second is effected by a contact 17 of relay H.

At each supply location the above named master signal control codes of 180 and 75 pulses per minute respectively are produced by contacts 180 and 75 of the code transmitters CT180 and CT75. The energy pulses of both of those master codes originate in battery TB and they are supplied to the track rails over a connection which includes a contact 1 of code repeating device CR. Under the driving influence of one or the other of the code transmitter contacts 180 and 75, repeating device CR so operates this contact 1 that it spaces the recurring pulses of signal code energy in the substantially equal "on" and "off" period manner represented at "master TB—CR code" in Fig. 1a.

In following one or the other of these two master signal control codes the track relay TR at each of the signal locations controls the decoding relays H and J in customary manner. These two relays respectively are "home" and "distant" devices and they receive pick-up energy from transformers T1 and T2. These transformers, in turn, are excited from a suitable source of direct current which is designated by the terminals B and C. Included in the exciting circuit of each is a pole changing contact 36 of the controlling track relay TR.

The "home" decoding relay H is adapted to pick up when the track relay TR responds to operating energy of either the 75 or the 180 code rate. It is a direct current device having sufficient release delay to span the code pulse spacings and receives from the secondary of transformer T1 energy that is rectified by a contact 37 of relay TR.

The "distant" decoding relay J receives its pick-up energy through a rectifier 27 from the secondary of transformer T2. That transformer, in turn, passes energy of an intensity sufficient to pick up the relay only when the code following relay TR responds to operating energy of the 180 pulse per minute code.

At each of the signal locations in the system, therefore, the elements just named cooperate to

cause both the "home" relay H and the "distant" relay J to pick up when the track relay TR is following code at the 180 pulse per minute rate; to allow only the "home" relay H to pick up when 5 the track relay responds to the slower 75 pulse per minute code; and to cause both of the relays H and J to release when the track relay TR ceases to follow code.

In determining the indication which is displayed by the controlled wayside signal S, the just described decoding relays H and J make use of the previously named contacts 21 and 34. Further included in the lamp lighting circuits of which these contacts form a part is a local energizing source B—C and a contact 8 of an approach control relay AR later to be described. As will become more evident presently, current of lighting intensity can be transmitted to the signal lamps G, Y and R only when relay AR is released.

When, under that condition, the track relay TR is responding to 180 pulse per minute code and both of the decoding relays H and J are picked up, the "clear" lamp G is lighted over back contact 8, front contact 21, the winding 40 of a relay KL (later to be described) and front contact 34; when the track relay is responding to 75 pulse per minute code and decoding relay H only is picked up, the "approach" lamp Y then 30 receives lighting current over back contact 8, front contact 21, winding 40 and back contact 34; and when the track relay TR fails to follow code and decoding relays H and J are both released, the "stop" lamp R is lighted over back 35 contact 8 and back contact 21.

In selecting the coding of the master signal control energy which is supplied to the track section to the rear, each of the decoding relays H (contact 17) is aided by a contact 18 of the just 40 named relay KL at the same location. For purposes of preliminary analysis it may be assumed that this contact 18 stays picked up as shown.

When, under that condition, the track relay TR is responding to coded energy at either the 45 180 or the 75 pulse per minute rate and decoding relay H is picked up, the repeating device CR which codes the signal control energy for the rear track section is driven by contact 180 of transmitter CT180 over a circuit that includes front contacts 17 and 18. When, however, the track relay TR fails to follow code and decoding relay H is released, the driving circuit for coding device CR is transferred by contact 17 (back point thereof) to the contact 75 of code transmitter CT75 and the rear track section then receives the 75 (instead of the 180) pulse per minute signal control code.

The apparatus so far described (with the exception of the relays AR and KL) is that which 60 ordinarily is included in a conventional "frequency-code" system of automatic block signaling.

Under vacant conditions of the protected stretch such a conventional system sets all of the controlled wayside signals S at "clear" and supplies the rails of each section with master signal code energy at the 180 pulse per minute rate. When, however, a train enters the stretch (from the left in Figs. 2—2a—3) and advances 65 past signals S1, S2, S3, etc., it successively de-energizes the track relays TR at those locations and thus successively conditions: (1) each of the named signals S1, S2, S3, etc., to show "stop"; (2) each associated coding device CR and track

battery TB to supply the rails of the section to the rear with energy of the 75 pulse per minute code; and (3) the first and second signals behind each "stop" displaying device to show "approach" and "clear."

Approach energization of signals S, decoding relays H—J, and coding devices CT—CR

The previously mentioned approach-control relays AR form a part of an approach energizing scheme which reduces the power consumption of the controlled traffic governing apparatus by maintaining the signals S, the decoding relays H—J and the coding devices CT—CR deenergized at all times except when an approaching train requires that these several devices be brought into action to provide it with a signal indication.

This approach-energizing scheme also includes a pair of approach-detector relays KRX and KRD which are provided at each location and which will be more completely described presently. Through the medium of contacts 19 and 20, those approach-detector relays govern the energization of the approach control relay AR at the same location. Whenever either one of the relays KRX and KRD is picked up, relay AR receives energizing current from source B—C over the front point of contact 19 or 20 and by that current is held picked up. When, however, both of the relays KRX and KRD are released, the just named energizing circuit is broken and relay AR then releases.

When picked up, each relay AR keeps the lamps of the associated wayside signal S deenergized. This function is performed by contact 8 which, under vacant conditions of the signaled stretch, disconnects lighting source terminal B from lamp-selector contact 21 of decoding relay H. Cooperating with contact 8 in its control of lamps G and Y are the windings 39 and 40 of the before named relay KL. These windings respectively have relatively high and relatively low resistances. In consequence current of lighting intensity can reach lamps G and Y only by way of contact 21 and winding 40 but not by way of contact 33 and winding 39.

The signal location relays KL perform light-out protecting functions later to be described and they do this through the medium of the before named contacts 18. For reasons later to be made evident each of these relays is designed to pick up whenever current (from source B—C) is passed through either of the two windings 39 and 40 thereof and to release only when both of those windings become deenergized.

In order that the decoding relays H and J at each location will be supplied with energizing current only when a train approaches, the pick-up transformers T1 and T2 therefor are at proper times disconnected from their exciting source B—C by contacts 5 and 9 of the before named approach detector relays KRX and KRD. Whenever those detector relays are either both picked up or both released, the associated decoding relays receive pick-up current in normal manner. When, however, either of the relays KRX and KRD is released at a time when the other is picked up, the mentioned disconnection occurs and exciting current then is removed from transformers T1 and T2.

For the purpose of bringing the code producing devices CT—CR at each location into action only when a train approaches, the driving circuits therefor are at proper times disconnected from their energizing source B—C by contacts 6 and 7

of the just mentioned approach-detector relays KRX and KRD. Whenever relay KRD is released or whenever relay KRX is picked up, the code-producing devices CT—CR are connected (over contact 6 or 7) with their energizing source and they then operate in normal manner. When, however, relay KRD is picked up at a time when relay KRX is released, the mentioned disconnection occurs at contacts 6 and 7 and devices CT—CR are then rendered inactive.

The novel track circuit combination of Fig. 1

Serving to determine the positions of the two approaching-detector relays KRX and KRD at each signal location are rearwardly extending track circuit facilities of the novel character most clearly represented by Fig. 1. There a single track section D—E is shown as being equipped with the same trackway apparatus as is each of the signal blocks V2, V3 and V5 of the complete system of Figs. 2—2a—3.

Comprised by this apparatus are: (1) at the section exit end E the previously named source of master signal code energy TB, the coding device CR, and the approach-detector relay KRX and KRD; and (2) at the section entrance end D the previously named code following track relay TR, a source of direct current trackway energy AB, a source of alternating current trackway energy ALT, and a connection reverser relay PC.

The two exit end approach-detector relays KRD and KRX respectively are operated by and only by direct current energy from entrance end source AB and by alternating current energy from entrance end source Alt. The direct current relay KRD thus is unresponsive to alternating current energy. It is connected with the section rails over the back point of a contact 4 of coding device CR when that device is at rest and also during the "off" periods of the master signal control code which contact 1 of the same device at times produces. This relay KRD is short circuited over the front point of contact 4 during each rail connection separating interval and it has a release delay which is sufficient to span those intervals as long as they do not substantially exceed code period duration.

The alternating current approach-detector relay KRX is continuously connected with the section rails over a rectifier K and a resonant unit TI. That unit includes a combined inductance and condenser circuit which freely passes alternating current energy having the frequency of entrance end source Alt., but which excludes from the relay all direct current energy from both of the sources AB and TB.

Alternating current source Alt. may conveniently take the form of a tuned alternator which when excited by direct current generates a commercial frequency (as 60 cycles per second) alternating current output voltage having the character represented at "Alt. energy" in Fig. 1a. In the arrangement shown this output voltage is transmitted to the section rails through a transformer TT and a resistance R. It is produced only when the alternator exciting circuit is connected with source B—C over contacts 5 and 9 (see Figs. 2—2a—3) of relays KRX and KRD at the same location. Under vacant conditions of section D—E it then holds exit end relay KRX continuously picked up as long as the supply thereof to the section rails continues.

In order that the signaling system track relay TR will not be falsely picked up by the just described alternating current energy from source

Alt., it is designed to respond to and only to unidirectional energizing current from one or the other of direct current sources TB and AB.

Direct current source AB may take the form of a battery which is similar to but preferably of lesser voltage than exit end battery TB. Connection of this source AB with the section rails occurs only when contacts 2 and 3 of the reverser relay PC are released. Under that condition battery AB energizes the rails over a circuit extending from the positive terminal of that battery through back contact 3 of device PC, the winding of track relay TR, impedance I, back contact 2 of device PC, conductors 45 and 44, the section rails, and conductor 47 back to the negative terminal of battery AB.

When the track section D—E is vacant the rails thereof are thus maintained by battery AB at a steady difference of potential, such as is represented at "AB energy" in Fig. 1a. At the section exit E this rail potential energizes approach-detector relay KRD over a circuit extending from one of the section rails through conductor 43, the winding of relay KRD, back contact 4 of coding device CR, and conductors 50 and 48 back to the other section rail.

As a result of this energization relay KRD is held continuously picked up both when the coding device contact 4 is following code and when that contact is continuously released. Under the latter condition the relay winding current has the uninterrupted character indicated at "AB energy" in Fig. 1a. Under the former the relay winding current is interrupted during each "on" period of the "master TB—CR code" of Fig. 1a, and thus is given the pulsed character indicated at "AB—TB energy" in Fig. 1a. Because of its slow releasing design, however, relay KRD stays continuously picked up when energized in this recurring pulse manner.

The connection reverser relay PC of the novel Fig. 1 combination has two windings 51 and 52 of relatively high resistance. At proper times these windings are energized over circuits which the composite diagram of Figs. 2—2a—3 shows (at each of the signal locations therein) as including contacts 6 and 7 of detector relays KRX and KRD and the lamps G and Y of the wayside signal S. This energization originates in source B—C and it occurs only when contacts 6 and 7 are both picked up. Under that condition winding 51 receives current which flows to source terminal C through the filament of signal lamp G and winding 52 receives current which reaches terminal C through the filament of lamp Y.

These PC relay windings 51 and 52 are preferably so designed that the current drawn by each is insufficient to illuminate the series connected signal lamp and that simultaneous energization of both is required to pick up the relay contacts 2 and 3. Those contacts, of course, are released (as shown in Fig. 1) as long as the windings 51 and 52 remain deenergized.

When picked up, however, the just named contacts 2 and 3 of the entrance end relay PC connect the track relay TR directly across the rails through an impedance I; when released the same contacts reverse the track relay connection and additionally include therein the direct current source AB. When so included source AB impresses upon the track rails the before described steady potential. This potential polarizes the rails in the same relative manner as does that of the exit end battery TB.

Because of this relation, the track relay TR follows the coding action of contact 1 of exit end device CR when the reverser relay PC is released as well as when that relay is picked up.

- 5 Under the latter condition, of course, each "on" period pulse of master signal control code (see the "master TB—CR code" portion of Fig. 1a) energy from the exit end battery TB that is transmitted to location D picks up track relay 10 TR over a circuit extending from the positive terminal of battery TB through an impedance 42, conductor 43, one of the track rails, conductors 44 and 45, front contact 3 of device PC, the winding of relay TR, impedance I, front contact 2 of device PC, conductors 46 and 47, the other track rail, conductor 48, front contact 1 of device CR, conductor 49 and a resistance R back to the negative terminal of battery TB.
- 15 Under the former condition (device PC released) the entrance end received pulses of master code energy (from battery TB) also cause the track relay TR to follow the master energy coding. Now, however, the pick-up current for relay TR is supplied by entrance end battery AB and the releases of relay TR are produced by the neutralizing or series-opposing pulses of signal code energy from exit end battery TB.

20 This AB-supplied pick-up current reaches the track relay TR over a circuit previously traced as extending from the positive terminal of battery AB through back contact 3 of device PC, the winding of relay TR, impedance I, back contact 2 of device PC, conductors 45 and 44, the 25 track rails (together with apparatus at the section exit end), and conductor 47 back to the negative terminal of battery AB.

25 During each "off" period of the master signal control code the current (see "AB—TB energy" portion of Fig. 1a) flowing from battery AB into the section rails picks up the track relay TR and there holds it until the succeeding "on" period pulse of signal code energy is received from battery TB. Upon that reception the potential 30 between the rails is maintained by battery TB and in consequence the drain on battery AB is interrupted. Now deprived of pick-up current, relay TR releases and there stays until the succeeding signal code "off" period when the resumed current drain on battery AB again picks it up.

35 It will accordingly be seen that when the track section D—E is vacant and the reverser relay PC is released the track relay TR picks up in step with the "off" periods of the entrance end received "master TB—CR code," and releases in step with the "on" periods of that code. When, however, the exit end coding device CR is continuously released or when section D—E becomes occupied the represented released condition of relay PC causes the battery AB to supply the rails with uninterrupted current which holds the track relay TR continuously picked up.

40 65 Operation of the complete systems of Figs. 2—2a—3

70 As already pointed out, the complete system of Figs. 2—2a—3 provides each of the signal blocks V therein with track circuit facilities which are a duplicate of those just described for section D—E of Fig. 1. In operation of that complete system those facilities cooperate with each other and with the remaining trackway ap-

paratus illustrated in a manner which will now be explained.

As long as all of the represented signal blocks V remain vacant, the equipment for each of those blocks has the condition which is shown for section V5 of Fig. 3. Under that condition: (1) at the section entrance end the reverser relay PC is disconnected (at contact 6) from its pick-up source and hence is released, the track relay TR receives from battery AB steady energy which holds it continuously picked up, and the alternator Alt. is disconnected (at contacts 5 and 9) from its exciting source and hence is inactive; and (2) at the section exit end the detector relay KRD receives (over the rails) from entrance end battery AB steady energy which holds it picked up, the detector relay KRX receives no alternating current energy and hence is released, the coding device CR (along with its transmitters CT) is disconnected (at contacts 6 and 7) from its operating source and hence also stays released, and the master track battery TB is disconnected (at contact 1) from the section rails.

In consequence each of the approach-control relays AR is energized (over contact 20) and thereby held picked up, each of the wayside signals S is disconnected (at contact 8) from its lighting source and hence maintained deenergized, each set of decoding relays H—J is disconnected (at contacts 9 and 5) from its pick-up source and hence kept deenergized, and each set of coding devices CT—CR is disconnected (at contacts 7 and 6) from its operating source and also maintained deenergized.

Under the just discussed unoccupied conditions of the signalled stretch, therefore, the only energy sources in the system that are subject to power drain are the entrance end track batteries AB. Those batteries are, as already pointed out, connected with the rails of the several sections for the purpose of holding the exit end detector relays KRD therefor picked up. All other energy sources (including the exit end track batteries TB and the control sources B—C) will be seen to be completely free from drain.

Now let it be assumed that a train vehicle traveling from left to right enters the stretch by way of section V1 of Fig. 2. In that figure such a vehicle is represented at M. In shunting the rails of section V1 vehicle M produces the following actions.

At the location of signal S2 this shunt of block V1 deenergizes and releases detector relay KRD1. Thus released, contact 9 of that relay now conditions decoding relays H1 and J1 for response to track relay TR1 (by connecting transformers T1 and T2 with their exciting source) and also brings alternator ALT1 into action; contact 1 now connects coding devices CT1—CR1 with their energizing source; and contact 20 now releases approach relay AR1. This latter release sets up (over back contact 8) the lighting circuits for signal S2. Reverser relay PC1 remains released because of the break in its pick-up circuit at contact 1. Under these conditions battery AB1 supplies (over back contacts 2 and 3 of device PC1) the rails of signal block V2 with direct current energy and alternator ALT1 supplies (through transformer TT1) the same rails with alternating current energy.

At the location of signal S3 these two forms of energy respectively continue detector relay KRD2 picked up (over back contact 4 of device

CR2) and shift detector relay KRX2 from its released to its picked up position. As a result of this shift contact 5 of device KRX2 now conditions decoding relays H2 and J2 for response to track relay TR2 and also brings alternator ALT2 into action; and contact 6 now connects coding devices CT2—CR2 with their energizing source and also picks up reverser relay PC2. This pick-up of relay PC2 disconnects (at contacts 2 and 3) battery AB2 from the rails of signal block V3 and connects track relay TR2 directly across those rails. Under the just stated conditions the block V3 rails receive only alternating current energy (from source ALT2) at the block entrance end.

At the location of signal S4 this alternating current energy shifts detector relay KRX3 from its released to its picked up position. At the same time the absence of rail-transmitted direct current energy at that point allows detector relay KRD3 to release. As a result of these two actions contacts 5 and 9 continue devices ALT3 and H3—J3 in their previously deenergized conditions; and contacts 6 and 7 continue reverser relay PC3 released but now connect coding devices CT3—CR3 with their energizing source.

In consequence of the continued release of relay PC3 and the deenergization of device ALT3, the rails of the forwardly extending block V4b—V4 which signal S4 guards now receive only direct current energy from entrance end source AB3 and they thus have the normal or "vacant track" condition which already has been described by reference to block V5 of Fig. 3. This same condition, moreover, is shared by succeeding blocks of vacant track still further ahead.

At the location of signal S4, in addition, the above stated energization of coding devices CT3—CR3 and the deenergization of decoding relays H3—J3 causes the rails of rearwardly extending block V3 to be supplied with signal control energy coded at the 75 pulse per minute rate. This energy is derived from master track battery TB3 at the block exit; the recurring pulses thereof are transmitted to the rails over front contact 1 of coding device CR3; and that device, in turn, receives driving energy over contact 15 of code transmitter CT75.3 by way of a circuit which includes back contact 18 of relay KL3.

At the entrance end of block V3 (location of signal S3) the code following track relay TR2 receives the pulses (see "master TB—CR code" portion of Fig. 1a) of this 75 code signal control energy by way of front contacts 2 and 3 of device PC2. In picking up and releasing in step with those received pulses, this track relay TR2 picks up the "home" decoding relay H2 (but produces no response on the part of the "distant" relay J2). Relay H2, in turn, completes (at front contact 33) a pick-up circuit for relay KL2. Now, accordingly, contacts 17 and 18 of devices H2 and KL2 establish (over their front points) a circuit over which code repeating relay CR2 is driven by contact 180 of code transmitter CT180.2.

At the location of signal S3, in consequence, the rails of the rearwardly extending block V2 now are supplied with signal control energy coded at the 180 pulse per minute rate. This energy is derived from master track battery TB2 at the block exit and the recurring pulses thereof are transmitted to the rails over front contact 1 of coding device CR2.

At the entrance of block V2 (location of sig-

nal S2) the track relay TR1 now follows the coding of this 180 pulse per minute signal control energy which is there received. During this action, however, each "on" period of the received signal control code produces a release on the part of track relay TR1 (due to its serial connection with battery AB1 over back contacts 2 and 3 of device PC1) and each "off" period of that code allows current from battery AB1 to pick the track relay up. (For further explanation see the earlier description of the "TB-AB energy" portion of Fig. 1a.)

In thus responding to the 180 pulse per minute signal control code of block V2, track relay TR1 causes the pick-up of both of the decoding relays H1 and J1. Contacts 21 and 34 thereof now complete the lighting circuit for lamp G of signal S2 and cause that signal to display the "clear" indication. By that indication the engineman of train M (in block V1 of Fig. 2) is advised that the advance blocks V2 and V3 are both vacant.

Were block V3 to be occupied then this same signal S2 would show "approach" instead of "clear" when a train (such as M of Fig. 2) requires an indication therefrom. In the event of such V3 block occupancy, track relay TR2 at the entrance end of that shunted block would cease to follow code, decoding relay H2 would release contact 17 and transfer the driving circuit for coding device CR2 from transmitter CT180.2 to transmitter CT15.2, the rails of block V2 then would receive signal control energy coded at the 75 pulse per minute rate, track relay TR1 at the block entrance end now would follow that slower code, decoding relay J1 would release contact 34, and lamp Y of signal S2 would now light to show that only the advance block V2 is vacant.

And finally, were this block V2 to be occupied, then signal S2 would display to the approaching train M of Fig. 2 the most restrictive or "stop" indication. In the event of such V2 block occupancy, track relay TR1 at the entrance end of that shunted block would cease to follow code, decoding relay H1 would release contacts 17, 33 and 21, and under the control of contact 21 lamp R of signal S2 would now light to show that the next block in advance was occupied. Concurrently, of course, the signal control energy supplied to the rails of block V1 would be transferred (by contact 18 of the now released relay KL1) from the 180 to the 75 pulse per minute coding.

From the last three paragraphs it will accordingly be seen that the normally-inactive coded track circuit system of Figs. 2-2a-3 provides the customary three-indication form of automatic block signal control and that the following protection afforded thereby is in no way impaired by the energy-conserving and other improvements of which that normally inactive system makes use.

Thus, each train which proceeds through the signaled stretch of Figs. 2-2a-3 brings into action such coding and other devices ahead as are needed to indicate the condition of the track sections which the train is about to enter. This action will be most readily understood through reference to Fig. 4. In that figure the arrows pointing upwards and downwards indicate the picked up and the released conditions respectively of the two detector relays KRX and KRD for each of the stretch sections V1-V2-V3-V4^b-V4 when each of those sections is successively occupied by the train vehicle M.

The showings of Fig. 4 for the positioning of vehicle M in block section V1 have already been described in detail. Under that condition it has been seen that relays KRX1 and KRD1 are released, that relays KRX2 and KRD2 are picked up, that relay KRX3 is picked up while relay KRD3 is released, that relay KRX4^b is released while relay KRD4^b is picked up, and that relay KRX4 likewise is released while relay KRD4 is picked up.

From Fig. 4 it will be seen that advancement of the vehicle M from block section V1 into block section V2 moves ahead by exactly one signal block the combination of advance detector relay (KRX-KRD) positionings which the preceding paragraph sets forth; that further advancement of the vehicle into block section V3 moves the same positioning combination ahead another signal block; and so on. Because of this parallel movement of the advance range of detector relay responses the already explained signal indications are made available to the train M during its entire travel through the signaled stretch of Figs. 2-2a-3.

As, moreover, each block section in that stretch is vacated by the train the apparatus associated therewith restores itself to the normally inactive condition that is described at the beginning of this explanation on "Complete system operation." In leaving section V1, for example, train M allows steady energy from the entrance end source AB (not shown) to flow over the section rails to the exit end detector relay KRD1. In picking up that relay KRD1: (1) energizes approach relay AR1 over contact 20 and thus removes (at contact 8) lighting current from signal S2; (2) deenergizes (at contact 7) the coding devices CT1-CR1 for section V1; and (3) removes (at contact 9) the exciting current from decoding relays H1-J1 and from alternator ALT1 for section V2. For each succeeding block section that is vacated a similar set of actions takes place.

The various operations that have been explained for the signal blocks (such as V2, V3 and V5) of the Figs. 2-2a-3 system which contain only one track section each also takes place in blocks wherein more than one section is included. Such a multi-section block is shown in Figs. 2a-3 as being guarded by signal S4 and as embracing a rear section V4^b and a forward section V4.

At the junction of these two sections is apparatus which performs the "repeating" functions which are customary for cut locations. It includes devices KRX4^b, KRD4^b, CR4^b, TB4^b, TR4^b, AB4^b and ALT4^b which have the same general characteristics and organization as do the correspondingly identified devices at each of the signal locations. In this cut location organization, however, the following special arrangements are present.

The rear section coding relay CR4^b is driven by a contact 56 of the forward section track relay TR4^b; the driving circuit of which contact 56 forms a part is rendered effective only when the rear section detector relay KRX4^b picks up a contact 57 or when the rear section detector relay KRD4^b releases a contact 58; the forward section alternator ALT4^b is brought into operation only when the rear section detector relay KRX4^b picks up a second contact 59; and the contacts 2 and 3 which control the connection of the forward section rails with direct current source AB4^b and with track relay TR4^b are carried by

the rear section detector relay KRD^{4b} (instead of by a connection reverser relay PC as at the signal locations).

By virtue of these special cut location arrangements: (1) coded signal control energy received from the forward section is repeated (by devices TR^{4b}, CR^{4b} and TB^{4b}) into the rails of the rear section; (2) direct current approach control energy received from the rear section is repeated (by devices KRD^{4b}, and AB^{4b}) into the rails of the forward section; and (3) alternating current approach control energy received from the rear section also is repeated (by devices KRX^{4b} and ALT^{4b}) into the rails of the forward section.

Under vacant track conditions, in consequence, the two-section signal block V^{4b}—V⁴ functions (in the complete system of Figs. 2—2a—3) in the same manner as does each of the single-section signal blocks with which it is associated. When occupied by a forwardly moving train, likewise, this two-section signal block V^{4b}—V⁴ also functions in a manner which is fully equivalent to that of the single section blocks and which permits the before explained "complete system" actions to take place in the desired way.

The complete signaling system of the herein disclosed invention is further so organized that each of the signal location relays KL performs a light-out protection function which will now be explained by reference to device KL¹ at the location of signal S² of Fig. 2.

Under the conditions which are there represented for signal S², the "clear" lamp G thereof is lighted. Should, now, the filament of that lamp burn out, flow of current (over back contact 8, front contact 21 and front contact 34) through winding 49 of relay KL¹ would cease and that relay would release contact 18. That release, in turn, would transfer the driving connection of coding device CR¹ from contact 180 of transmitter CT180.1 to contact 75 of transmitter CT75.1. In consequence, the pulses of signal control code energy supplied to the rearwardly extending section V¹ then would be slowed to the lower or "caution" rate of 75 per minute.

Were, moreover, the lamp Y of signal S² to be lighted (as a result of contact 34 of decoding relay J¹ being released) instead of lamp G, a similar set of actions would result. That is, relay KL¹ would release and slow to the caution or 75 rate the pulses of signal control energy then supplied to the rails of section V¹.

Non-line-wire approach detection over three signal blocks

As the track circuit diagram of Fig. 1 shows and as the foregoing "system operation" description has brought out, the normal or vacant-track position of each set of the exit-end detector relays KRX—KRD is relay KRX released and relay KRD picked up. From the "relay response" diagram of Fig. 4, moreover, it has been seen that occupation of block V¹ by a train M alters this detector relay positioning as far ahead as the exit end of block V³; that occupation of block V² by the train registers on the detector relays as far ahead as the exit end of block V^{4b}—V⁴; that occupation of block V³ is indicated by the detector relays as far ahead as the exit end of block V⁵; and so on.

It will accordingly be evident that each train M which is within the signaled stretch of Figs. 2—2a—3 is at all times registered by the detector relays KRX—KRD at the exit end of: (1) the signal block which the train directly occupies;

(2) the first vacant block immediately in advance of the occupied block; and (3) the succeeding or second vacant block ahead.

By taking proper advantage of these detector relay registrations it at once becomes possible to detect the approach of a train as far in advance thereof as three full signal blocks. As will become more evident presently, this extended-range detection is effected solely through the medium of energy that is transmitted through the track rails and hence it requires no line-wire control circuits of any kind.

Various ways of registering changes in contact position of the detector relays KRX—KRD can, of course, be arranged. One which proves very satisfactory is shown in Fig. 5. There an indication relay AN is controlled by detector relays KRX and KRD through the medium of contacts 23 and 24 thereof. As long as both of the detector relays have their normal or vacant-track condition (wherein relay KRX is released and relay KRD is picked up), this indication relay AN is energized over the represented serial connection of back contact 23 of relay KRX with front contact 24 of relay KRD and thereby held picked up. When, however, relay KRD releases or relay KRX picks up, the just named connection is broken and the indication relay AN then releases.

The change in detector relay contact position by which such a release is produced may, of course, be further indicated by a signaling device of any suitable character. In Fig. 5 one such device is shown at SPN as being controlled by a contact 25 of relay AN. As long as that relay stays picked up, this signaling device SPN is kept deenergized and hence inactive. When, however, relay AN releases, contact 25 thereof completes the energizing circuit for signaling device SPN and thus brings that device into action.

In the complete system of Figs. 2—2a—3 this just described combination of Fig. 5 is utilized to govern the highway crossing signals SPN of Fig. 3. As previously stated, the function of those signals is to warn the users of highway PN whenever the intersected track section V⁴ is being approached or occupied by a train.

As long as signal blocks V², V³ and V^{4b}—V⁴ all remain vacant, the crossing signals SPN of Fig. 3 are maintained inactive as a result of their operation-governing relay AN⁴ being held picked up over back contact 23 of detector relay KRX⁴ and front contact 24 of detector relay KRD⁴. Such a condition is represented by Figs. 2—2a—3 and by Fig. 5. It persists even when block V¹ becomes occupied by a train as shown at M in the upper portion of Fig. 4.

From the time, however, that the train M first advances into the entrance end of block V² until it clears the exit end of section V⁴, the crossing signals SPN are brought into and kept in operation by a release of contact 25 of relay AN⁴. Reference to Fig. 4 and earlier given description will show that this release is produced in the following manner. When the train is in block V² the release results from a pick-up of detector relay KRX⁴ and a release of detector relay KRD⁴ which breaks the energizing circuit of relay AN⁴ at both contacts 23 and 24; when the train is in block V³ the release results from a pick-up of detector relay KRX⁴ which opens the AN⁴ relay circuit at contact 23; and when the train is in section V^{4b} and/or section V⁴ the AN⁴ release results from a release of detector relay KRD⁴ (accompanied by a release of detector relay

KRX4) which opens the AN4 relay circuit at contact 24.

Operation of the crossing signals SPN is discontinued as soon as the train M moves completely out of section V4 and into block V5. Upon that movement, of course, detector relays KRX4 and KRD4 resume their normal released and picked up positions wherein contacts 23 and 24 pick up relay AN4 and cause contact 25 thereof to break the SPN energizing circuit.

Summary

From the foregoing it will be seen that the invention herein disclosed has effected important improvements in signaling systems of the coded track circuit class and in apparatus for detecting the approach of trains without the aid of line wires.

In particular it has increased the utility and decreased the power requirements of automatic block signaling systems of the coded track circuit type; it has extended the distance over which the approach of a train may be detected by energy that is transmitted through the track rails; and it has effected the above through the use of apparatus of comparatively simple character and without dispensing with any of the desirable features of coded track circuit control.

As all of these improvements are primarily a function of the track circuits and apparatus which is directly associated therewith they are relatively independent of the coding and decoding facilities of the coded signaling systems which they may supplement and hence are usable with a wide variety of different types and forms of such facilities.

This invention, accordingly, is evidently not limited to the particular signaling system herein described and illustrated by way of example.

Having thus described my invention, what I claim is:

1. In combination, a section of railway track over which traffic moves in a given direction, a first track circuit for said section which includes a first track relay at the section entrance end and a source of direct current energy at the section exit end, a second track circuit for said section which includes a second track relay at the section exit end and a source of direct current energy at the section entrance end, apparatus which connects said entrance end source across the rails of said section in series with the winding of said first track relay and thereby allows current from said source to pass through said winding and maintain a given polarity difference of potential between said rails, other apparatus which at times is effective to connect said exit end source across said section rails in such a way as to establish between those rails a difference of potential that is of the aforesaid given polarity and that substantially discontinues the flow of said entrance end source current through the winding of said entrance end track relay and which at other times is effective to connect said exit end track relay across said rails in such a way as to impress thereon the said trackway potential that said entrance end source maintains, and traffic governing apparatus controlled by each of said two track relays.

2. In combination, a section of railway track, a first track circuit for said section which includes a code following track relay at the section entrance end and a source of direct current energy at the section exit end, a second track circuit for said section which includes a

detector track relay at the section exit end and a source of direct current energy at the section entrance end, apparatus which connects said entrance end source across the rails of said section

5 10 15 20 25 30 35 40 45 50 55 60 65 70 75

section in series with the winding of said code following track relay and thereby allows to pass through said winding current from said source which holds the track relay picked up and which maintains a given polarity difference of potential between said rails, coding apparatus which repeatedly connects said section rails first in given polarity establishing manner with said exit end source whereby to release said code following track relay by substantially discontinuing the flow of said entrance end source current therethrough and then directly with said detector track relay whereby to impress thereon the said trackway potential that said entrance end source maintains, and traffic governing apparatus controlled by said code following and detector track relays.

3. In combination, a section of railway track, a first track circuit for said section which includes a code following track relay at the section entrance end and a source of direct current energy at the section exit end, a second track circuit for said section which includes a detector track relay at the section exit end and a source of direct current energy at the section entrance end, apparatus which connects said entrance end source across the rails of said section in series with the winding of said code following track relay and thereby allows to pass through said winding current from said source which holds the track relay picked up and which maintains a difference of potential between said rails, a coding device which at times repeatedly connects said section rails first with said exit end source in such rail polarizing manner as to release said code following track relay by substantially discontinuing the flow of said entrance end source current therethrough and then with said detector relay whereby to impress thereon the said trackway potential that said entrance end source maintains and which at other times establishes said rail-to-detector relay connection uninterruptedly thereby causing said entrance end source then continuously to energize said code following and detector track relays in series, traffic governing apparatus controlled by said code following track relay and distinctively responsive according as that relay is or is not recurrently picking up and releasing, and other traffic governing apparatus controlled by said detector track relay and distinctively responsive according as that relay is or is not being energized from said entrance end source.

4. In combination, a section of railway track, a first track circuit for said section which includes a first track relay at the section entrance end and a source of direct current energy at the section exit end, a second track circuit for said section which includes a second track relay at the section exit end and a source of direct current energy at the section entrance end, exit end apparatus which at times connects the rails of said section with said exit end source in such manner that a given polarity difference of potential is established between those rails and which at other times connects said rails in energy supplying relation with said second track relay, entrance end apparatus which at times connects said section rails directly across the winding of said first track relay and thereby impresses on that winding the said given polarity

trackway potential that said exit end source establishes and which at other times connects said rails across said entrance end source through said first track relay winding in such series manner that current of relay pick-up intensity is passed by said entrance end source to said rails through said series connected winding when and only when said given polarity potential difference between said rails is not being established by said exit end source, and traffic governing apparatus controlled by said two track relays.

5. In combination, a section of railway track, a first track circuit for said section which includes a code following track relay at the section entrance end and a source of direct current energy at the section exit end, a second track circuit for said section which includes a detector track relay at the section exit end and a source of direct current energy at the section entrance end, apparatus which at times is effective to connect said entrance end source across the rails of said section in series with the winding of said code following track relay in a manner allowing to pass through said winding current from said source that holds the track relay picked up and that maintains a given polarity difference of potential between said rails and which at other times is effective to connect the said code following track relay winding in direct energy receiving relation with said rails, a coding device which during recurring "on" code periods connects said section rails with said exit end source in such given polarity establishing manner as to release said code following track relay under its first stated condition of serial connection and to pick up that relay under its second stated condition of direct connection and which during intervening "off" period intervals connects said rails with said detector track relay whereby to impress thereon the said trackway potential that said entrance end source maintains, and traffic governing apparatus controlled by said code following and detector track relays.

6. In combination, a section of railway track, a first source of direct current energy for said section at the exit end thereof, coding apparatus which connects said exit end source with the rails of said section in periodically interrupted manner and thereby produces a trackway code made up of recurring "on" period pulses of rail potential that are separated by "off" period intervals, a code following track relay for said section at the entrance end thereof, a second source of direct current energy for said section at the entrance end thereof, apparatus effective at times to connect the winding of said track relay directly across said section rails and thereby cause that relay to pick up and release in respective step with the "on" period pulses and the "off" period intervals of the entrance end received said trackway code potential and effective at other times to connect said entrance end source across the section rails through said track relay winding in such series manner that current of relay pick-up intensity is passed by said entrance end source through said winding to said rails only during the "off" periods of said received trackway code whereby during those other times said track relay releases and picks up in respective step with said "on" and "off" periods of that received code.

7. In combination, a section of railway track over which traffic moves in a given direction, a first track circuit for said section which includes a source of direct current energy at the section exit and an entrance end code following track re-

lay that is unresponsive to alternating current energy and that at all times follows the coding of pulsed direct current energy which said exit end source may transmit to the section entrance, a second track circuit for said section which includes a source of direct current energy at the section entrance and a first exit end detector track relay that is unresponsive to alternating current energy and that is operable by and only by unidirectional energy from said entrance end direct current source, a third track circuit for said section which includes a source of alternating current energy at the section entrance and a second detector track relay at the section exit that is unresponsive to direct current energy and that at all times responds to there received energy from said alternating current source, a coding device for at times connecting said exit end direct current source with the section rails in periodically interrupted manner whereby under vacant track conditions to produce code following operation on the part of said entrance end track relay, means for at times connecting said entrance end direct current source with said rails whereby under vacant track conditions to pick up said first exit end detector track relay, means for at times causing said alternating current source to supply energy to said rails whereby under vacant track conditions to pick up said second exit end detector track relay, traffic governing apparatus controlled by said code following track relay and distinctively responsive according as that relay is or is not recurrently picking up and releasing, and other traffic governing apparatus controlled by said first and second detector track relays and distinctively responsive to each combination of picked up and released positions thereof.

8. In combination: a stretch of railway track which includes a plurality of consecutively adjoining track sections and through which traffic moves in the direction of from the first to the second of said sections; a first track circuit for each of said sections which includes a source of direct current energy at the section entrance and at the section exit a first detector track relay that is responsive to direct current energy from said entrance end source but not to alternating current energy; a second track circuit for each of said sections which includes a source of alternating current energy at the section entrance and at the section exit a second detector track relay that is responsive to energy from said entrance end alternating current source but not to direct current energy; means controlled by the said two detector track relays at the exit of each of said sections for connecting the rails of the next section in advance with the said two entrance end sources therefor in such selective manner that those rails receive direct current energy only under certain conditions of approaching traffic, both direct current and alternating current energy under other approaching traffic conditions, and alternating current energy only under still further conditions of approaching traffic; and traffic governing apparatus at selected of said section exit ends controlled by the said two detector track relays which are there located.

9. In combination: a stretch of railway track which includes a plurality of consecutively adjoining track sections and through which traffic moves in the direction of from the first to the second of said sections; a first track circuit for each of said sections which includes a source of direct current energy at the section entrance and at the section exit a first detector track relay

that is responsive to direct current energy from said entrance end source but not to alternating current energy; a second track circuit for each of said sections which includes a source of alternating current energy at the section entrance and at the section exit a second detector track relay that is responsive to energy from said entrance end alternating current source but not to direct current energy; means controlled by the said two detector track relays at the exit end of each of said sections for connecting the rails of the next section in advance with the said two entrance end sources therefor in such selective manner that those rails receive only direct current energy when the two sections immediately to the rear of the supply location are both unoccupied, only alternating current energy when only the first section immediately behind the supply location is vacant, and both direct current and alternating current energy when that first rearwardly extending section is occupied; and traffic governing apparatus at selected of said section exit ends controlled by the said two detector track relays which are there located.

10. In combination: a stretch of railway track which includes a plurality of consecutive adjoining track sections; a following-protection coded track circuit for each of said sections which includes at the section entrance end a source of direct current energy together with normally inactive coding apparatus that when brought into action recurrently connects said source with the section rails at a code pulse rate determined by traffic conditions in advance and at the section entrance end a code following track relay that is unresponsive to alternating current energy and that follows the coding of the pulsed direct current energy which said exit end source at times transmits to said entrance end; a first approach-control track circuit for each of said sections which includes at the section entrance a source of direct current energy and at the section exit a first detector track relay unresponsive to alternating current energy and operable by and only by unidirectional energy from said entrance end direct current source; a second approach-control track circuit for each of said sections which includes a source of alternating current energy at the section entrance and a second detector track relay at the section exit that is unresponsive to direct current energy and that is operable by the received energy from said alternating current source; means controlled by the said two detector track relays at the exit end of each of said sections for connecting the rails of the next section in advance with the said two entrance end sources therefor in such selective manner that those rails receive only direct current energy when the two sections immediately to the rear of the supply location are both unoccupied, only alternating current energy when only the first section immediately behind the supply location is vacant, and both direct current and alternating current energy when that first rearwardly extending section is occupied; and control means at the exit of each of said sections for bringing the there located said section coding apparatus into action when the there located said direct current detector track relay is released or when the there located said alternating current detector track relay is picked up whereby each train passing through the stretch initiates operation on the part of the said coded track cir-

cuit in the occupied section and in each of the two sections immediately thereahead.

11. In combination: a stretch of railway track which includes a plurality of consecutively adjoining track sections; a coded track circuit for each of said sections which includes at the section exit end a source of direct current energy together with coding apparatus that recurrently connects said source with the section rails at a 10 code pulse rate determined by traffic conditions in advance and at the section entrance end a code following track relay that is unresponsive to alternating current energy and that follows the coding of the pulsed direct current energy which said exit end source transmits to said entrance end; entrance end decoding apparatus for each section which normally is deenergized and hence inactive but which when supplied with exciting energy responds distinctively to each rate at which the there located said section track relay follows code; a first approach-control track circuit for each of said sections which includes at the section entrance a source of direct current energy and at the section exit 20 a first detector track relay operable by and only by unidirectional energy from said entrance end direct current source; a second approach-control track circuit for each of said sections which includes a source of alternating current energy at the section entrance and a second detector track relay at the section exit operable by and only by energy there received from said alternating current source; means controlled by the said two detector track relays at the exit end of each of said sections for connecting the rails of the next section in advance with the said two entrance end sources therefor in such selective manner that those rails receive only direct current energy when the two sections immediately to the rear of the supply location are both unoccupied, only alternating current energy when only the first section immediately behind the supply location is vacant, and both direct current and alternating current energy when that first rearwardly extending section is occupied; and control means at the exit end of each of said sections for supplying the said decoding apparatus at the entrance of the there adjoining advance section with exciting energy when the there located said direct current detector relay is released or when the there located said alternating current detector track relay is picked up whereby each train that passes through the stretch causes to come into action the said decoding apparatus at the entrance end of each of the three vacant sections immediately ahead of the train.

12. In combination: a stretch of railway track which includes a plurality of consecutively adjoining track sections; a coded track circuit for each of said sections which includes at the section exit end a source of direct current energy together with coding apparatus that recurrently connects said source with the section rails at a code pulse rate determined by traffic conditions in advance and at the section entrance end a code following track relay that is unresponsive to alternating current energy and that follows the coding of the pulsed direct current energy which said exit end source transmits to said entrance end; entrance end decoding apparatus for each section which normally is deenergized and hence inactive but which when supplied with exciting energy responds distinctively to each rate at which the there located

said section track relay follows code; an entrance end signal for each of said sections controlled by the there located said decoding apparatus but normally maintained deenergized; first and second approach-control track circuits for each of said sections respectively including an entrance end source of direct current energy together with a first exit end detector track relay operable only by energy from said direct current source and an entrance end source of alternating current energy together with a second exit end detector relay operable only by energy from said alternating current source; means controlled by the said two detector track relays at the exit end of each of said sections for connecting the rails of the next section in advance with the said two entrance end sources therefor in one selective manner when the track

stretch is vacant and in successive other selective manners when a train approaches the detector relay location; means also governed by each of said pairs of detector track relays and effective 5 when a train comes into the section to the immediate rear thereof for then exciting the said decoding apparatus at the entrance ends of the said two sections that are immediately ahead of the relays whereby to make indication control 10 available to the said signals at those two advance section entrance ends; and a circuit for supplying energizing current to each of said signals whenever the said two detector track relays at the location of the signal both become released due to a train entering the section to the 15 immediate rear.

LOUIS GIRARDIN.
